UNITED STATES PATENT OFFICE.

RICHARD HAWKE ROGERS, OF LONDON, ENGLAND.

CONCRETE PAVING, FLOOR, AND THE LIKE.

Application filed September 3, 1924. Serial No. 735,674.

To all whom it may concern:

Be it known that I, RICHARD HAWKE ROGERS, a British subject, and resident of 9 Park Place, London, S. W. 1, England, have invented certain new and useful Improvements in Concrete Paving, Floors, and the like (for which I have filed an application in England, No. 218,159, dated September 12th, 1923), of which the following is a specification.

This invention relates to concrete paving, concrete floors and other like structures made with metallic reinforcement. According to the present invention the reinforcement employed consists of plates of sheet metal cut so as to form tongues which can be bent out of the plane of the plate, these tongues serving to support or interconnect metal rods or wires in a plane at a distance from that of the plate, such rods, wires or the like being intended to act as binding members for the concrete, or in cases of reversed stress as tension members. The metal plate from which the tongues are bent may have cross-pieces left extending diagonally across the rectangles from which the tongues are cut, whereby the plate will be materially strengthened without interfering with the free passage of the concrete through the plate, and the thorough interconnection of the concrete below and above the surface of the plate. The tongues of the plate serve to form roughly pyramidal cells for the concrete, while the intervening spaces form portions of inverted pyramids, and it has been found by experiments when the concrete is more or less divided up in this way by the reinforcement that its resistance to deformation or fracture is very high. The invention comprises the reinforcement per se as an article of manufacture and also concrete structures embodying such reinforcement.

The invention is illustrated in the accompanying drawings, wherein:

Figure 1 is a perspective view of a portion of reinforcing structure according to the invention.

Figure 2 is a plan view thereof, and

Figure 3 a side view.

Figure 4 is a detail view showing a method of securing reinforcing rods or wires to the tongues.

Figure 5 is a plan view of a portion of a roadway with the reinforcement laid thereon in interconnected sections. 55

Figure 6 shows a cross-section of a roadway made according to the invention.

Figures 7, 8 and 9 are partial views showing various arrangements of the reinforcing 60 wires.

Referring first to Figures 1 to 4, it will be seen that the basis of the reinforcement consists of metal sheeting from which tongues *a* are cut and bent upwardly, leaving diagonal members *b* in the cells between the tongues. In this particular example binding wires *c* are laid along the tips of the tongues and are secured by bending over portions of the tips. Figure 4 shows a suitable method of bending. Near the tip of each tongue a subsidiary tongue is cut and the metal of this tongue is bent as at *d* around the wire, or so as to form an eyelet through which the wire can be threaded. 70 The actual tip *e* of the tongue is bent outwardly in order to provide an additional anchorage for the reinforcement in the concrete. 75

In laying a roadway for example, a number of sections of reinforcement made as above described are laid one beside another with their edges *g* overlapping, and the sections are then interconnected by wire lacing *f* carried around the roots of the tongues *a* 80 from one section to another. The sections may of course be bolted or riveted together if preferred, but the method of lacing as above described is sufficient for most purposes. The sections of the reinforcement 85 may be of any convenient dimensions, and in the example shown in Figure 5 the sections are in strips each of the width of two cells but of a length of eight cells. Obviously the sections might be shorter and 90 wider if preferred.

The reinforcement is laid on a comparatively shallow bed of concrete and then the concrete is filled in to a level somewhat above the top of the reinforcement. In 100 Figure 6, for example, *h* represents the level to which the concrete is filled in, while the layer *i* represents a road-surfacing layer or cover applied after the concrete has set.

It will be obvious that any additional 105 reinforcement required, for example ties of

greater strength than the rods or wires *c*, may easily be introduced into the reinforcement, for instance in the longitudinal and transverse channels between the tongues *a*.
5 The reinforcing wires *c* may also be applied in various different ways. For example, Figure 7 shows how the wires may be passed diagonally through holes or slots as at *k* near the tips of the tongues. The 10 wires may also be threaded straight through the holes *k* in the tongues as indicated in Figure 8, or the wiring may be provided as in Figures 7 and 8 combined in the one structure. As another alternative indicated 15 in Figure 9, the wiring of Figures 1 to 6 may be retained while the tongues *a* have holes or slots through them at a lower level as at *l*, through which additional wires may be passed, either longitudinally and trans- 20 versely as shown, or diagonally if preferred, as in Figure 7. It is unnecessary to illustrate all the possible ways in which the wiring may be combined with the tongues, but it is thought that the illustrations above 25 referred to will suffice for this purpose. The body portions of the tongues *a* may have subsidiary tongues cut and bent out from them if required, as indicated at *o* in Figure 1. These tongues *o* provide further pro- 30 jecting engaging members for the concrete and they may also serve as a means of supporting additional reinforcing bars if required. Instead of being flat in the spaces between the principal tongues *a*, the sheet 35 metal plate may be stamped with ridges or the like for the purpose of increasing its stiffness, and the tongues *a* themselves may be stamped out with ridges therein for the same purpose, although this is not generally necessary.
40 Where the binding rods or wires *c* cross one another they may be interconnected either by wire binding as indicated at *n*, by spot welding or in any other convenient 45 manner. The wires may also be spot-welded, for example, to the tongues *a* instead of being passed through slots or otherwise secured thereto as previously described. It is not essential that the diagonals marked 50 *b* in the drawings should be left between the tongues, and when these diagonals are not required the tongues may be cut out by simple X-shaped slits being formed in the plate. It is preferred, however, to leave 55 the diagonals for strengthening purposes.
60 When the reinforcement is to be used for concrete flooring in buildings for example, the apertures in the plate may be closed from below by another plate applied at the bottom and connected, for example, by spot welding at convenient positions. The additional plate will then serve to support the concrete within the reinforcement formed in accordance with the present in- 65 vention.

The tongues *a* may be bent up from the plate at any convenient angle thereto, but as a rule it will be found most convenient for the tongues to be bent up to from 45° or more from the horizontal, and in the 70 example shown in the drawings they are bent up to about 60°.

Having thus described my invention what I claim as new and desire to secure by Letters Patent is:—

1. A reinforcement for concrete paving, floors and so forth comprising a metal plate, tongues cut out and bent up from said metal plate, and reinforcing elements supported by the tongues above the said metal plates so as to form an intersecting network of reinforcing elements. 80

2. A reinforcement for concrete paving, floors and so forth comprising a metal plate, tongues cut out and bent up from said metal plate, in groups of four so as to form substantially truncated conical cells over the surface of the plate, and reinforcing elements supported by the tongues above the said metal plate so as to form an intersecting network of reinforcing elements. 90

3. A reinforcement for concrete paving, floors and so forth comprising a metal plate, tongues cut out and bent up from said metal plate, and reinforcing elements supported by the tips of the tongues above the said metal plates so as to form an intersecting network of reinforcing elements. 95

4. A reinforcement for the purpose set forth comprising a metal plate, triangular tongues cut out and bent up from said plate at substantially 45° and reinforcing rods engaged by the tips of the tongues so as to form an intersecting network of rods above the level of said plate. 100

5. A reinforcement for the purpose set forth comprising a metal plate, triangular tongues cut out and bent up from said plate at substantially 45°, subsidiary tongues cut out in each tongue near the apex thereof, said subsidiary tongues being bent to form an eye, and reinforcing rods engaged by said eyes, the apices of the triangular tongues being bent over the rods and extending in a plane parallel to said plate. 110

6. A reinforcement for the purpose set forth comprising a metal plate, triangular tongues cut out and bent up from said plate at substantially 45° and reinforcing rods engaged by end portions of the tongues so as to form an intersecting network of rods above the level of said plate, the tips of the tongues being bent over the rods and extending in a plane parallel to said plate. 120

7. A reinforcement for concrete paving, floors and so forth comprising a metal plate, tongues cut out and bent up from said metal plate, diagonal connecting members in the areas of the plate from which the tongues are cut, and reinforcing elements supported 130

by the tongues above the said metal plate so as to form an intersecting network of reinforcing elements.

8. A reinforcement for concrete paving, floors and so forth comprising a metal plate, tongues cut out and bent up from said metal plate, projecting tongues cut from the tongues, and reinforcing elements supported by the tongues above the said metal plate so as to form an intersecting network of reinforcing elements.

9. A reinforcement of the character described comprising a metal plate, triangular tongues cut out of said plate, said triangular tongues being bent up from said plate at their bases at substantially 45°, diagonal connecting members extending across the space of said plate from which the triangular tongues have been cut, subsidiary tongues cut out of said triangular tongues and projecting outwardly therefrom, wire lacing at the roots of the triangular tongues, and reinforcing rods supported by said triangular tongues, said rods extending longitudinally and transversely over said plate so as to form a crossing network above the surface of said plate.

10. A concrete structure consisting of a reinforcement comprising a metal plate, tongues cut out and bent up from said metal plate, and reinforcing elements supported by the tongues above the said metal plate so as to form an intersecting network of reinforcing elements, and concrete in which said reinforcement is embedded, the concrete extending from the level of the base plate to above the reinforcing elements.

11. A concrete structure consisting of a reinforcement comprising a metal plate, triangular tongues cut out and bent up from said plate at substantially 45°, and reinforcing rods engaged by the tips of the tongues so as to form an intersecting network of rods above the level of said plate, and concrete in which said reinforcement is embedded, the concrete extending from the level of

the base plate to above the reinforcing rods.

12. A concrete structure consisting of a reinforcement, comprising a metal plate, triangular tongues cut out and bent up from said plate at substantially 45°, and reinforcing rods engaged by end portions of the tongues so as to form an intersecting network of rods above the level of said plate, the tips of the tongues being bent over the rods and extending in a plane parallel to said plate, and concrete in which said reinforcement is embedded, the concrete extending from the level of the base plate to above the reinforcing rods.

13. A concrete structure consisting of a reinforcement comprising a metal plate, triangular tongues cut out of said plate, said triangular tongues being bent up from said plate at their bases at substantially 45°, diagonal connecting members extending across the space of said plate from which the triangular tongues have been cut, subsidiary tongues cut out of said triangular tongues and projecting outwardly therefrom, wire lacing at the roots of the triangular tongues, and reinforcing rods supported by said triangular tongues, said rods extending longitudinally and transversely over said plate so as to form a crossing network above the surface of said plate, and concrete in which said reinforcement is embedded, the concrete extending from the level of the base plate to above the reinforcing rods.

14. A concrete structure consisting of a reinforcement, comprising a metal plate, tongues cut out and bent up from said metal plate, in groups of four so as to form substantially truncated conical cells over the surface of the plate, and reinforcing elements supported by the tongues above the said metal plate so as to form an intersecting network of reinforcing elements, and concrete in which said reinforcement is embedded, the concrete extending from the level of the base plate to above the reinforcing elements.

RICHARD HAWKE ROGERS.
